(57) **CLAIM**

The ornamental design for a shoe heel, as shown and described.

DESCRIPTION

FIG. 1 is a side elevational view of a shoe heel showing my new design; and,

FIG. 2 is a rear elevational view thereof.

The design is directed to serve as a heel to a shoe. The shoe is shown in broken lines to indicate that it forms no part of the claimed design.

All surfaces not shown form no part of the claimed design.
